UNITED STATES PATENT OFFICE.

FREDERICK L. WHITE, OF WATERBURY, CONNECTICUT, ASSIGNOR TO
GEORGE H. CLOWES, OF SAME PLACE.

DESIGN FOR A LAMP-BODY.

SPECIFICATION forming part of Design No. 29,406, dated September 27, 1898.

Application filed July 30, 1898. Serial No. 687,365. Term of patent 14 years.

To all whom it may concern:

Be it known that I, FREDERICK L. WHITE, a citizen of the United States, residing at Waterbury, in the county of New Haven and

5 State of Connecticut, have invented a certain new and original Design for a Lamp-Body, of which the following is a specification, reference being had therein to the accompanying drawing.

10 My invention relates to a design for a portable lamp-body.

The leading feature of my design is a lamp-body of cylindrical form having rounded ends and provided with a central band.

In the drawing the numeral 1 designates 15 the lamp-body having the form of a cylinder, both ends of which are rounded, and 2 the band around the central portion thereof.

What I claim is—

15 The design for a lamp-body, substantially 20 as shown and described.

In testimony whereof I affix my signature in presence of two witnesses.

FREDERICK L. WHITE.
